LECTERN

Thomas J. Watson, New Canaan, Conn., assignor
to International Business Machines Corpora-
tion, New York, N. Y., a corporation of New
York

Application April 24, 1942, Serial No. 440,414

1 Claim. (Cl. 45—6)

This invention relates to tables and more particularly to a speaker's table such as, for example, a lectern or pulpit and it has for a broad object to provide a speaker's table which is of improved construction and arrangement of parts.

It is another object of this invention to provide an improved lectern or pulpit having ample and uniform illumination means, having a sound-proofed recessed portion for the placement of detachably connected microphones, and having lateral recesses for the disposition of notes, sheets and manuscripts.

Other objects of the invention will be pointed out in the following description and claim and illustrated in the accompanying drawing, which discloses, by way of example, the principle of the invention and the best mode, which has been contemplated, of applying that principle.

In the drawing:

Fig. 1 is a perspective view of the complete lectern.

Fig. 2 is a side elevation of Fig. 1 showing a partial view of the elevating mechanism.

The general features of the invention can best be understood from an examination of the drawing shown in Fig. 1. The lectern is here shown having a top 10 mounted in a base 11. Actually the top 10 is mounted upon a hollow box 12 which telescopes into the base 11 (see Fig. 2). The top 10 (see Fig. 1) is provided with a hood 13 at each end and an inclined front panel 14. In the center of the top 10 is a cork plate 15 upon which a speaker's manuscript may be placed and, on either side of this plate 15, a recessed portion 16 is cut into the top 10 to provide for additional manuscript storage. A tubular electric lamp 17 is mounted in each hood 13 at either end of the top 10 for providing even illumination of the top 10, plate 15, and the panel 14. A toggle switch 18 provides a means to control the lamps 17. On the left of the panel 14 is mounted a conventional electric clock 19, and on the right of the panel 14 a timer clock 20 is similarly mounted. A warning light 21 associated with the timer clock 20 is mounted on a subpanel attached to one of the hoods 13. Directly in back of the plate 15 (see Fig. 1) the panel 14 is recessed to provide space for mounting a plurality of microphones 23 in the receptacles 22, the electrical connections to such being led through said receptacles and into and through the base 11 (not shown for sake of simplicity). In the front of the top 10 is mounted a plate 24 having two push buttons 25 and 26, these being labelled "Raise" and "Lower" respectively. The push buttons 25 and 26 are for the purpose of manually controlling the oper-

ation of a motor driven gear mechanism 29 mounted within the base 11 so that the box-like structure 12 and top 10 may be raised and lowered with respect to the base 11 to suit the height requirements of the individual speaker. Upon the outside of one of the hoods 13 is a gavel block 27. The timer clock 20 is provided with a hand 28 which serves both as a non-elapsed time indicator and as a means to set the time clock in operation.

It is to be noted that the various panels and plates in top 10 are mounted upon cork or other sound proofing material, and that wherever possible, the panels themselves are of such composition.

While there has been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the intention, therefore, to be limited only as 25 indicated by the scope of the following claim.

What is claimed is:

A speaker's table comprising a base, a column-like supporting structure extending upwardly from said base; a top carried by the upper part 30 of said column-like structure and being formed with a rear part behind which a speaker may stand, a front part opposite said rear part, and a pair of ends joining, respectively, the adjacent ends of said rear and front parts; said top also 35 including a centrally located plate providing an upper surface adapted to support the speaker's notes when being used, and said top being formed with a recess in the front part thereof disposed forward of said plate and having a defining wall 40 part arranged below the level of adjacent parts of the note supporting surface and said recess being adapted to contain acoustic detectors; said top also including a pair of similar wall members extending laterally from the two opposite sides, 45 respectively, of said plate and extending below the level of said plate and terminating outwardly adjacent said two ends to provide a pair of storage places for notes not being used, symmetrical- 50 ly disposed on opposite sides of said plate; the two ends of said top including wall means providing a pair of lamp shades adapted to contain lamps therein and said shades being constructed so that they open inwardly toward said plate to direct light thereon from both sides.

THOMAS J. WATSON.
